United States Patent Office

Des. 181,597
Patented Dec. 3, 1957

181,597

FIREPLACE

Jack W. Mosher, Saginaw, Mich.

Application January 20, 1956, Serial No. 39,867

Term of patent 3½ years

(Cl. D81—7)

FIG - 1

I claim:

The ornamental design for a fireplace, as shown and described.
